CLAIM

The ornamental design for a bullet case, as shown and described.

DESCRIPTION

FIG. 1 is a top perspective view of a bullet case showing our new design;

FIG. 2 is a perspective view thereof with the top open; FIG. 3 is a bottom rear perspective view of FIG. 1; FIG. 4 is a top perspective view of an alternate embodiment of the bullet case;

FIG. 5 is a perspective view thereof with the top open and the interior separators as shown in FIG. 2 removed for convenience of illustration; and

FIG. 6 is a bottom rear perspective view of FIG. 4.

FIG. 1

FIG. 2

FIG. 3
